UNITED STATES PATENT OFFICE.

CHARLES L. FERRIOTT, OF BARTLETT, TEXAS, ASSIGNOR OF ONE-HALF TO
EDWARD FORD, OF SAME PLACE.

TIRE-TIGHTENER.

SPECIFICATION forming part of Letters Patent No. 632,706, dated September 12, 1899.

Application filed June 19, 1899. Serial No. 721,131. (No model.)

To all whom it may concern:

Be it known that I, CHARLES L. FERRIOTT, a citizen of the United States, residing at Bartlett, in the county of Williamson and State of Texas, have invented a new and useful Tire-Tightener, of which the following is a specification.

The invention relates to improvements in tire-tighteners.

10 The object of the present invention is to improve the construction of tire-tighteners and to provide a simple, inexpensive, and efficient device adapted to serve as a spoke-socket and capable of enabling a tire to be 15 readily tightened or adjusted to prevent a wheel from becoming dished.

The invention consists in the construction and novel combination and arrangement of parts hereinafter fully described, illustrated 20 in the accompanying drawings, and pointed out in the claims hereto appended.

In the drawings, Figure 1 is a sectional view of a tire-tightener constructed in accordance with this invention and showing the simpler 25 form thereof. Fig. 2 is a detail perspective view of the thimble. Fig. 3 is a similar view of the screw. Figs. 4 and 5 are sectional views showing the preferred form of my invention.

30 Like numerals of reference designate corresponding parts in all the figures of the drawings.

Referring more particularly to Figs. 1, 2, and 3 of the accompanying drawings, in which 35 is illustrated the simpler form of my invention, 1 designates a thimble receiving the outer end 2 of a spoke 3 and provided with a reduced outer portion 4, forming a tenon and fitting in an opening 5 of a felly 6, and 40 the shoulder 7, formed by the reduction of the thimble, engages the felly 6 at the inner edge thereof, as clearly illustrated in Fig. 1 of the accompanying drawings. The spoke 3 has its outer end 2 reduced to fit within the 45 body portion of the thimble, and the shoulder 8, formed by this reduction, engages the edges of the thimble. The reduced end 2 of the spoke is provided with a slot or bifurcation 9, arranged at the center and receiving a flange or projection 10 of a screw 11.

The screw 11, which is provided at its inner end with a head 12, has the flange or projection 10 formed integral with the same and arranged centrally thereon, being disposed longitudinally of the screw. The flange or 55 projection 10 bears against the wall at the inner end of the slot or bifurcation, and the head 12 fits against the end of the spoke at opposite sides of the said slot or bifurcation, whereby the inner end of the screw has a firm 60 bearing against the end of the spoke.

The outer reduced portion of the thimble is provided with interior screw-threads 13, which are engaged by the screw, which is held stationary by being interlocked with the outer 65 end of the spoke in the manner before described. When it is desired to tighten the tire 14, the thimble is rotated to expand the rim of the wheel, and the device which forms an efficient support for the outer end of the 70 spoke is adapted to maintain the tire perfectly tight as long as the wheel lasts, whereby the durability of the wheel is greatly increased. The thimble may be rotated by a pipe-wrench or any other suitable tool, and, 75 if desired, it may be provided with a wrench-seat or with a socket to be engaged by the projection of a spanner.

In Figs. 3 and 4 of the accompanying drawings is illustrated the preferred form of my 80 invention, and the outer end of the spoke is supported by a fixed ferrule or sleeve 15, tapering as shown and provided at its outer end with an inwardly-extending annular flange, forming a reduced opening for the reception of the screw. The inner enlarged portion 17 of the thimble 18 has a polygonal outer face and forms a seat for a wrench, whereby the thimble may be readily rotated. The fixed sleeve or ferrule of the spoke forms 85 a wear-plate for the same to prevent the spoke from being worn by the thimble.

The invention has the following advantages: The device, which is exceedingly simple and inexpensive in construction, possesses great strength and durability, and it forms an efficient spoke-socket and tire-tightener. It is adapted to tighten the tire of a wheel in warm weather, when the wood shrinks, and it is capable of adjusting the 90 100

parts to prevent the wheel from becoming dished when the woodwork swells in damp weather.

Changes in the form, proportion, size, and 5 the minor details of construction within the scope of the appended claims may be resorted to without departing from the spirit or sacrificing any of the advantages of this invention.

What is claimed is—

- 10 1. In a device of the class described, the combination with the rim of a wheel, and a spoke having its outer end bifurcated, of a thimble receiving the end of the spoke and provided with a reduced outer portion forming a shoulder to engage the rim of the wheel and interiorly threaded, and a screw engaging the threads of the thimble and provided at its inner end with a head fitting against the end of the spoke and having a flange or 15 projection extending into the bifurcation,
- 20

whereby the screw is detachably interlocked with the spoke and is held rigid therewith, substantially as described.

2. In a device of the class described, the combination with the rim of a wheel, and a 25 spoke of a sleeve or ferrule mounted on the outer end of the spoke, a stationary screw interlocked with the spoke, and a rotary thimble forming a tenon to engage the rim of the wheel, and having its inner portion enlarged 30 to receive the outer end of the spoke and provided with a wrench-seat and engaging the sleeve or ferrule, substantially as described.

In testimony that I claim the foregoing as my own I have hereto affixed my signature in 35 the presence of two witnesses.

CHARLES L. FERRIOTT.
